UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

BUCKET WHEEL AND METHOD OF MAKING SAME.

Application filed December 9, 1920. Serial No. 429,535.

To all whom it may concern:

Be it known that I, CHRISTIAN STEENSTRUP, a citizen of the United States, residing at Schenectady, in the county of Schenectady, State of New York, have invented certain new and useful Improvements in Bucket Wheels and Methods of Making Same, of which the following is a specification.

10 This application is a continuation in part of my application, Serial No. 272,588, filed January 22, 1919, bucket wheels and method of making the same.

15 The invention relates to bucket wheels for elastic fluid turbines which wheels comprise a disc to the periphery of which buckets are fastened, and has for its object to provide an improved wheel and method of making the same.

20 For a consideration of what I believe to be novel and my invention, attention is directed to the accompanying description and the claims appended thereto.

25 In the drawing, Fig. 1 is a diagrammatic view illustrating my invention; Fig. 2 is a view partly broken away and with certain parts in section of a fragment of a completed bucket wheel; Fig. 3 is a short section of a strip with openings punched there-in; Fig. 4 is a section through the central portion of Fig. 1, and Fig. 5 is a view similar to Fig. 2 of a modification.

30 Referring to the drawing, 5 indicates a disc which forms the web of a bucket wheel and which may be made from plate stock or other material. It may have the thickness found desirable for any particular case. Fig. 1 may be considered a bottom plan view and in carrying out my improved method disc 5 is fixed to an index plate 6 having notches 7 in its periphery corresponding to the number of buckets the completed wheel is to have. Preferably the notches 7 are spaced apart an angular distance equal to that which the buckets are to be spaced. Pivoted to the center of index plate 6 is a lever 8 having a spring-pressed pawl 9 which engages notches 7. At 9^a is a suitable cam in engagement with which lever 8 is held by a spring 10. Cam 9^a may be rotated in any suitable manner to oscillate lever 8, thus imparting a step by step movement to index plate 6 and disk 5. Backward turning of plate 6 is prevented by a spring-pressed holding pawl 11. As

disk 5 is turned there is wound on its periphery a metal strip 12 in which are punched holes 13 of a contour to receive the base of a turbine bucket. A short section of this strip is shown in Fig. 3. A punch for 60 making holes 13 is indicated at 14. It may be of any suitable character and arranged to operate in synchronism with lever 8 so that a hole 13 will be punched in strip 12 just after each movement of disk 5. Or, 65 in other words, the punch 14 makes a hole 13 after which lever 8 advances the disk 5 one notch.

70 In order that the index plate 6 may advance exactly one notch at a time, I provide 70 an arrangement whereby lever 8 is in frictional engagement with plate 6 so that on the return movement lever 8 will pull the plate 6 to bring the teeth of plate 6 into firm engagement with pawl 11. To this end 75 I provide the inner end of lever 8 with a sleeve 20, Fig. 4, which passes through an opening in plate 6 and has a nut 21 on its outer end between which and the face of the plate is a disk 22 and a rubber ring 23. 80 Disk 22 is suitably splined to sleeve 20 so that it turns with the sleeve. By turning down nut 21, plate 6 may be frictionally clamped to the desired degree between the inner end of lever 8 and disk 22. 24 is a 85 locking bolt for holding the parts just described in position. With this arrangement, after index plate 6 has been advanced by pawl 9 so that holding pawl 11 drops in the next notch and the return movement of 90 lever 8 begins the frictional engagement between lever 8 and plate 6 will pull plate 6 back to bring the particular tooth into firm engagement with pawl 11.

95 As the disk 5 is advanced step by step strip 12 is wound thereon, the holes in successive layers of strip 12 coinciding and when the desired number of layers has been wound the strip is cut off and the end temporarily fastened. After the end of the 100 strip has been fastened, buckets 15, as indicated in Fig. 2, are assembled around the disk with their bases stuck into holes 13. The bucket band or shroud ring 16, which is made up in a round ring, is now heated 105 and slipped over the outer part of the buckets. When the bucket band 16 cools it shrinks and consequently forces the buckets against the periphery of the bucket wheel or disk 5.

In some cases and when found desirable, as for example, in the case of small wheels, the bucket ends may be provided with tenons for riveting the bucket cover in place.

- 5 Under these circumstances the bucket cover will be shrunk down over the tenons as shown in Fig. 2 and the tenons then upset in the usual manner to hold the bucket cover in place. In other cases it may be desirable 10 to utilize buckets without tenons and this arrangement is illustrated in Fig. 5. In this case the bucket cover 16 which is in the form of a continuous ring is shrunk around the buckets. After the bucket cover is in place 15 the bucket wheel may be removed from the index plate, if this has not already been done, after which the bucket bases, the disk, and the successive turns of the strip are united by fusion of metal, as by being 20 brazed or welded together in the well understood manner, or otherwise fastened together. This then forms in substance a solid unit. The bucket cover may or may not be fastened by fusion of metal as found 25 desirable. In general, when of the structure shown in Fig. 5, it will be so fastened.

It will be noted that lever 8 always moves disk 5 the same angular distance and as the diameter of the disk increases, due to successive layers being wound thereon, the holes 30 13 will be automatically spaced farther apart so the holes in successive layers will align correctly.

By the above-described method, I produce 35 a bucket wheel which is strong and light in weight and which can be produced at a relatively low cost as regards labor, for all the operations required are simple and little machine work is required. Also the 40 buckets need not have specially shaped and finished bases but may be of the same contour through their length. This greatly simplifies the manufacture of the buckets.

In accordance with the provisions of the 45 patent statutes, I have described the principle of operation of my invention, together with the apparatus which I now consider to represent the best embodiment thereof; but I desire to have it understood that the apparatus shown is only illustrative, and that 50 the invention can be carried out by other means.

What I claim as new and desire to secure by Letters Patent of the United States, is:—

55 1. The method of making bucket wheels, which comprises winding successive layers of strip material having spaced openings therein about a disk so the openings in successive layers coincide, inserting the bases 60 of buckets in the openings, and fastening the disk, layers and bucket bases together.

2. The method of making bucket wheels, which comprises winding successive layers of strip material having openings therein 65 about a disk so the openings in successive

layers coincide, inserting the bases of buckets in the openings, and brazing or welding the disk, layers and bucket bases together.

3. The method of making bucket wheels, 70 which comprises taking a disk, winding successive layers of strip material thereon by a step by step movement and simultaneously punching holes in said strip, the holes being punched during the interval of time between 75 steps, inserting the bases of buckets in the holes, and brazing or welding the disk, layers and bucket bases together.

4. The method of making bucket wheels, 80 which comprises winding successive layers of strip material having spaced openings therein about a disk so the openings in successive layers coincide, inserting the bases of buckets in the openings, placing a ring which has been heated to expand it around 85 the bucket, permitting the ring to cool whereby it will shrink and force the buckets into the openings, and fastening the disks, layers and bucket bases together.

5. The method of making bucket wheels, 90 which comprises taking a disk, winding successive layers of strip material thereon by a step by step movement and simultaneously punching holes in said strip, the holes being punched during the intervals of time 95 between steps, inserting the bases of buckets in the holes, shrinking a ring around the outer ends of said buckets, and brazing the discs, layers and bucket bases together.

6. The method of making a bucket wheel 100 which comprises taking a disk, mounting a ring of buckets around it in a temporary manner, shrinking a bucket cover on the buckets, and then uniting the whole by fusion of metal.

7. The method of making a bucket wheel 105 which comprises taking a disc, mounting a ring of buckets around it and shrinking a continuous bucket cover around the ends of the ring of buckets to grip them tightly 110 between the periphery of the wheel and the cover, and then uniting the disk, buckets and ring by fusion of metal.

8. A bucket wheel comprising a disk having wound thereon successive layers of strip 115 material, said successive layers having aligned holes therein, and buckets having their bases fixed in said holes.

9. A bucket wheel comprising a disk having wound thereon successive layers of strip material, said successive layers having aligned holes therein, and buckets having their bases located in said holes, said disk, layers and bucket bases being brazed or 120 welded together.

10. A bucket wheel comprising a disk having wound thereon successive layers of strip material, said successive layers having aligned holes therein, buckets having their bases fixed in said holes, and a bucket cover 130

comprising a continuous ring which encircles the buckets.

11. A bucket carrying member comprising a disk having wound thereon successive layers of strip material, said successive layers having aligned holes therein, buckets having their bases fixed in said holes, said buckets having smooth ends, and a continuous bucket cover shrunk on said buckets.

12. A bucket wheel having wound thereon successive layers of material.

13. A bucket wheel the rim of which is formed of a plurality of successive layers of material located one on top of another and united to each other by fusion of metal.

14. A bucket wheel having wound thereon successive layers of material and buckets fastened therein.

15. The method of making a turbine element which comprises taking a carrying member, fastening thereon a member having openings therein at spaced intervals, mounting fluid directing elements on the carrying member with their ends in said openings and held in place by said member having the openings, and fastening such ends and members together by fusion of metal.

16. The method of making a turbine rotor element which comprises taking a carrying member, fastening thereon a member having openings therein at spaced intervals, mounting buckets on the carrying member with their inner ends in said openings, and held in place by said member having the openings, mounting a member around the other ends of the buckets, and fastening the parts together by fusion of metal.

17. The method of making a turbine rotor element which comprises taking a circular carrying member, mounting thereon a continuous member having spaced open-

ings, mounting a ring of buckets on the carrying member with their ends in the 45 openings in said second member and held in place by such member, and fastening the bucket ends and members together by fusion of metal.

18. The method of making a turbine rotor 50 element which comprises taking a supporting member, a member having openings therein at spaced intervals, and buckets, assembling the parts with the second named member on the supporting member and the 55 buckets with their ends fastened in said openings whereby said buckets are held by such second named member, and permanently uniting the whole by fusion of metal.

19. The method of making a turbine rotor 60 element which comprises taking a carrying member, a continuous strip of material having openings therein, and buckets, initially assembling them in a temporary manner with the buckets fastened in the openings 65 and the strip on the carrying member, and permanently uniting said buckets, strip and member by fusion of metal.

20. A turbine element comprising a carrying member, a ring united to said carrying member by a brazing or welding material, said ring presenting spaced openings, and fluid directing elements fixed in said openings, and held by said ring.

21. A turbine element comprising a carrying member, a ring united to said carrying member by a brazing or welding material, said ring presenting spaced openings, and fluid directing elements fixed in said 75 openings by brazing or welding material, 80 whereby said fluid directing elements are held by said ring.

In witness whereof, I have hereunto set my hand this 8th day of December, 1920.

CHRISTIAN STEENSTRUP.
